UNITED STATES PATENT OFFICE.

JOSEPH A. MUDD, OF CHICAGO, ILLINOIS, ASSIGNOR TO CHICAGO
BINDER & FILE COMPANY, OF CHICAGO, ILLINOIS, A CORPO-
RATION OF ILLINOIS.

LOOSE-LEAF BINDER.

No. 828,201

Specification of Letters Patent.

Patented Dec. 11, 1906.

Application filed March 12, 1906. Serial No. 305,626.

To all whom it may concern:

Be it known that I, JOSEPH A. MUDD, a citizen of the United States, residing at Chicago, in the county of Cook and State of Illinois, have invented a new and useful Improvement in Loose-Leaf Binders, of which the following is a specification.

My invention relates particularly to loose-leaf binders for use in connection with price-books, note-books, and the like, and my primary object is to provide a binder of this character of exceedingly simple and cheap construction and possessing great durability and thoroughly adapted to the purpose for which it was devised.

The invention is illustrated in its preferred embodiment in the accompanying drawings, in which—

Figure 1 represents an end elevational view 20 of a book constructed in accordance with my invention; Fig. 2, a plan view of the binder-frame; Fig. 3, a section taken as indicated at line 3 of Fig. 2; Fig. 4, a section taken as indicated at line 4 of Fig. 2, showing the binder 25 in its closed condition; and Fig. 5, a section similar to Fig. 4, but showing the binder in the open condition.

The book comprises, in the preferred embodiment, a binder A and flexible cover-section B, joined by a back portion b. The binder A comprises a pair of end bars a; a pair of rock-shafts a', having their end portions journaled in the end portions of the end members a; impaling prongs or hooks a", carried by the rock-shafts a'; a pair of toggle-joints a³, joining the intermediate portions of the rock-shafts; a centrally-located tie member a⁴, joining the rock-shafts; filler-blocks a⁵, confined between the rock-shafts, said blocks being of light material, such as wood or cardboard, and a flexible strip of leather or the like a⁶, having its lateral edges joined to the base portions of the cover-sections, the frame portion of the binder being confined 35 between the flexible member a⁶ and the back member b of the book and said flexible member being provided with slots a⁷ for the prongs a² and with slots a⁸ for the toggle-joints a³. The end members a of the binder-frame have perforations which fit upon reduced portions at the ends of the rock-shafts, the rock-shafts being shouldered adjacent to the end bars and having their extremities up-

set or riveted to form the connections. The rock-shafts preferably comprise small circular resilient rods. The prongs may be of any suitable form. One member of each pair of prongs is preferably provided with a reduced extremity received by a socket in the end of the other member of the pair. Each toggle-joint a³ preferably comprises a pair of arms a⁹ a¹⁰, fixedly secured to the rock-shafts and having their ends joined by a pivot a¹¹. The tie member a⁴ preferably comprises a flat spring resting upon the rock-shafts and having 65 downwardly and inwardly curved extremities partially encircling the rock-shafts. The filler-blocks a⁵ are recessed at their lateral edges to partially embrace the rock-shafts.

In the open condition of the binder (shown 70 in Fig. 5) the rock-shafts are parallel and not under flexure. In this condition, also, the spring tie member a⁴ loosely connects the rock-shafts and is not under flexure. When the binder is closed, as indicated in Figs. 2 75 and 4, the toggle-joints produce flexure of the rock-shafts and also produce tension and flexure of the tie member a⁴, the member a⁴ in this condition frictionally gripping the rock-shafts, thus tending to prevent the 80 opening of the binder. The combined length of the arms a⁹ a¹⁰ of each toggle-joint is greater than the normal distance between the rock-shafts, so that the rock-shafts are sprung when the arms are depressed from the 85 position shown in Fig. 5 to the position shown in Fig. 4, as by closing the jaws of the binder. The construction is such that the pivot a¹¹ passes slightly below the plane of the axes of the rock-shafts during the closing 90 of the binder, so that the flexure of the rock-shafts tends to prevent opening of the binder.

The binder may be supplied with any number of toggle-joints serving to produce flexure of the rock-shafts, and the engaging ends of 95 the arms constituting each toggle-joint may be joined by a pivot, as shown, or the pivot may be omitted. The binder may be used with or without the tie member a⁴ and with or without the filler-blocks a⁵. Not only is 100 the binder of simple and economical construction, but the form of the binder-frame is such as to enable the binder-frame to be well and economically connected with the back and cover-sections in the manner shown.

The foregoing detailed description has been

given for clearness of understanding only and is not to be regarded as in the nature of an undue limitation.

What I regard as new, and desire to secure 5 by Letters Patent, is—

1. A binder comprising a pair of rock-shafts, impaling-prongs carried by said rock-shafts, members connecting said rock-shafts, and a toggle-joint operating to produce flexure of the rock-shafts, for the purpose set forth.
2. A binder comprising a pair of end members, a pair of rock-shafts pivotally connected therewith, impaling-prongs carried by said 15 rock-shafts, and a toggle-joint connecting the rock-shafts between said end members and operating to produce flexure of the rock-shafts, for the purpose set forth.
3. A binder comprising end members, a 20 pair of rock-shafts pivotally connected therewith, prongs carried by said rock-shafts, and a pair of arms rigidly connected with the rock-shafts and having engaging ends located above the plane of the axes of the rock-shafts in the open condition of the binder, said arms 25 adapted to spring the rock-shafts when the binder is closed, for the purpose set forth.
4. A binder comprising a pair of rock-shafts, impaling-prongs carried by said rock-shafts, connecting means joining said rock-shafts at their ends, an intermediate tie member, and an intermediate pair of arms fixed to

the rock-shafts and of greater length than the normal distance between the rock-shafts in the open condition of the binder, said arms 35 operating to spring the rock-shafts during the operation of closing the binder.

5. A binder comprising end members, a pair of rock-shafts pivotally connected therewith and equipped with prongs, and a toggle-joint connecting said rock-shafts between 40 said end members, in combination with cover-sections, a back member connecting said cover-sections, and a flexible member having its lateral edges joined to the base portions of 45 said cover-sections, said flexible member confining the binder-frame between the flexible member and said back member.

6. A binder comprising a pair of end members, a pair of rock-shafts journaled therein, 50 an intermediately-located toggle-joint connecting said rock-shafts, a filler in the space between the rock-shafts, and prongs carried by the rock-shafts, in combination with cover-sections, a back member joining said 55 cover-sections, a flexible member joining the base portions of the cover-sections and having slots receiving said prongs, for the purpose set forth.

JOSEPH A. MUDD.
